(57) **CLAIM**

The ornamental design for a wearable fishing rod holder, as shown.

DESCRIPTION

FIG. 1 is a front perspective view of a wearable fishing rod holder showing my new design;

FIG. 2 is a rear perspective view thereof;

FIG. 3 is a top plan view thereof;

FIG. 4 is a front elevational view thereof;

FIG. 5 is a right side elevational view thereof;

FIG. 6 is a rear elevational view thereof; and,

FIG. 7 is a left side elevational view thereof.

The bottom plan view is a mirror image of: FIG. 3 top plan view.

No claims are made for shading lines or small dots showing areas of cushioned materials, shading lines and dots are for illustrative purposes only.
